TWO THREAD CHAIN STITCH SEWING MACHINE

Nerino Marforio, Milan, Italy, assignor to S.p.A.
Virgilio Rimoldi & C., Milan, Italy

Filed Feb. 26, 1957, Ser. No. 642,442

Claims priority, application Italy Aug. 3, 1956

2 Claims. (Cl. 112—197)

This invention relates generally to sewing machines and specifically to improvements in two thread chain-stitch sewing machines for adapting these machines for attaching fabric bands and strips in the manufacture of outer knitted garments.

A principal object of the invention is to provide an improved machine capable of carrying out at an extraordinarily increased speed in an operation or step preparatory to linking or a like operation which had to be carried out heretofore on low speed machines at high cost and required the use of skilled operators, for carrying out the step.

An object of the invention is to provide an improved machine having a special guide system through which finishing ribbed edges or fabric strips can be attached to knitted garments at a speed of about 4000 stitches per minute as against 250 stitches per minute on the known knitted fabric sewing or linking machines.

Another object is to provide a special guide system by which it is possible to position and move along the folded fabric strip in an automatic manner.

Still another object is to provide a machine capable of effecting substantial savings through elimination of the preparatory step and lower cost of installation and operation of the machine, inasmuch as the improved machine is less expensive than a linking machine, requires less skilled operators and performs a similar operation in a shorter time.

The characteristic features of the machine will be understood from the specification and appended claims and as described in the accompanying drawings in which:

Fig. 1 is a perspective view of a double chain stitch sewing machine which has been adapted in accordance with the invention,

Fig. 2 is a fragmentary detail view on an enlarged scale of the machine shown in Fig. 1,

Fig. 3 is an elevational view of a structural detail of the machine shown in Figs. 1 and 2,

Fig. 4 is an end elevation view of the structure shown in Fig. 3 as viewed from the lefthand end of the structure,

Fig. 5 is a plan view of the structure shown in Fig. 3,

Fig. 6 is a plan view of a needle plate of the sewing machine in accordance with the invention,

Fig. 7 is a lefthand end view of the needle plate shown in Fig. 6, with the plate shown in a vertical position only for purpose of accommodating it in the drawings,

Fig. 8 is a perspective, exploded view of the needle plate shown in Fig. 6 and is illustrative of the assembly of the needle plate,

Fig. 9 is a side elevation view of a presser foot of the machine in accordance with the invention,

Fig. 10 is a sectional view taken on line X—X of Fig. 9,

Fig. 11 is a plan view of the presser foot shown in Fig. 9,

2

Fig. 12 is a sectional view taken on line XII—XII of Fig. 10,

Fig. 13 is a fragmentary perspective view of a ribbed band or finishing strip suitable for use of the machine and illustrates the folded position in which the workpiece is guided through the machine,

Fig. 14 is a fragmentary perspective view illustrative of the manner in which the workpiece shown in Fig. 13 is stitched to a garment according to the invention,

Fig. 15 is an enlarged view of the stitch pattern used in Fig. 14,

Fig. 16 is a fragmentary perspective view illustrative of a backing strip for attachment to a knitted garment,

Fig. 17 is a fragmentary view partly in section of the strip guide system according to the invention and illustrates the manner in which the elements forming the guide system cooperate to carry out the guiding function according to the invention,

In accordance with the drawings a double chain stitch sewing machine M is provided with a plate 1 having apertures or holes 1a for securing it to a tiltable cover member K, with machine screws 1b in the manner shown in Fig. 1. The machine has a vertically operable needle bar B for reciprocably operating a needle C and a presser bar H disposed substantially parallel to the needle bar spaced therefrom in a direction of advancement of a workpiece as later herein described.

Plate 1 is provided, at an offset portion 1c thereof as shown, with a pivot screw 2 and washer 3 providing a pivot for a rocker arm 4 having a stepped profile and provided with a longitudinal slot 5 (Figs. 2, 3 and 5) for guiding a slide 6 extending transversely of the rocker arm 4. The arm extends in length from its pivot point to edge 1d of plate 1. The slide 6 can be moved the full length of the slot 5 and locked in a set position by a knobbed member 8. The slide 6 has fixed thereto a bearing or guide plate 7 extending vertically to rocker arm 4 and having a side surface substantially facing the needle bar B and presser bar H, and functioning in the manner later herein set forth.

The rocker arm 4 may be angularly positioned to a fine adjustment by an eccentric washer 9 abutting the arm and rotatably pivoted on a pivot 10. A needle plate 11 is provided and has a portion 11a and a narrower portion 11b extending parallel to portion 11a and a part thereof, extending longitudinally therefrom and constituting a portion of the needle plate farthest removed from the needle and presser bars. The portion 11b is provided with an angular member 12 extending laterally from a longitudinal edge 11e of the portion 11b parallel to portion 11a as shown in Fig. 6 and having an upper surface thereof substantially flush with the upper surface of the plate 11. The longitudinal edge 11e is normal to a transverse axis of the plate portion 11a. Portion 11a of plate 11 is provided with a slot 13 through which the needle can pass during a stitching operation and is further provided with a bevel surface 11c functioning in the manner later herein set forth. The portion 11a has a longitudinal edge 11d parallel to a longitudinal edge 11f of portion 11b. The edges 11e and 11f are parallel to each other.

The invention comprises a presser device (Figs. 9 through 12) constituting a support member 14 having a split clamp 15 which can be taken up with a screw 16 for releasably clamping the presser foot device on the presser bar H. The device comprises a presser foot 17 having a slot 17a corresponding in position with the slot 13 of the needle plate for allowing the needle to move therethrough in carrying out a stitching operation in the manner set forth hereinafter.

The presser foot 17 is pivotally secured to support 14 by a threaded spindle 18. An auxiliary presser foot 19

is provided bearing on portion 11b of the needle plate and is secured by a pin 20 to a plunger 21 movable upwardly and downwardly in a carriage 17' and constantly biased in a downward direction by a spring 23 having one end thereof bearing on top of the plunger 22 and the opposite end secured to the carriage 17' by a threaded screw 23a. The auxiliary presser foot is provided with an orthogonal extension member 19a disposed above and spaced from the member 12 and having substantially an overall length equalling the length of member 12 and has a vertical portion 19b forming a guide surface as disclosed hereinafter.

As stated heretofore, the present invention is intended for adapting a double chain stitch sewing machine to carry out the stitching of a finishing strip or band for example, a ribbed knitted strip 24 (Fig. 13) intended to be attached to an edge of a knitted article of wear to serve as trimming, for instance, for the neck, or arm-hole, or bottom edge of the knitted garment or article of wear. The ribbed band is manufactured, for example, on straight or circular knitting machines (not shown) with a ribbed knit ratio of 1/1, or 2/1 or some similar ratio and is utilized any time a soft and flexible fabric is required. An edge 24b thereof is finished by a selvedge during manufacture and edge 24c is not in order to leave a separating thread when knitted on the straight or circular knitting machines. In order to attach the strip 24 it is folded at fold lines 24a. A lower flap 25 is bent inwardly into the folded strip 24. This flap 25 has a maximum width c of one centimeter. It being understood that the width of the upper flap or portion MN is equal to the width of the flap or portion XY so that the strip is uniform and symmetrical in dimensions.

The strip 24 is fed longitudinally automatically by the machine (Fig. 17) for securing to a garment 26 with flap 25 held under a lower surface of member 12 and the folded edge bearing on plate 7. The top flap MN of strip 24 enters a channel formed between guide plates 7 and 19b with member 19a underlying the upper flap thereby to hold the flaps spaced to allow an edge of a garment 26 to be disposed in the folded strip 24 in the manner shown and overlying the needle plate 11. The flap MN assumes the position MN' shown in dotted lines once it passes past the needle plate and presser arrangement of the invention. It being understood that presser foot 17 also underlies the upper flap of strip 24 in the manner shown with surface 17c smoothly functioning to assist in separating the flaps. It can be seen that an edge 1b of plate 1 is substantially in the same vertical plane and aligned with longitudinal edge 11d of needle plate 11 with the plate 1 being disposed at a lower level than the needle plate 11. In this manner the aforementioned elements form a guide system for guiding the strip 24 in folded relationship during a stitching operation.

If a stiffer fabric is required to serve as a backing or support a strip 28 folded at 28a with selvedge at both edges 28b may be provided and sewn to a knitted article 29 by means of stitches such as 27. It being understood that the guide system functions in a similar manner with respect to strip 28 as described with respect to strip or band 24.

While a preferred embodiment of the invention has been shown and described it will be understood that many modifications and changes can be made within the scope of the invention.

What I claim is:

1. In a two thread chain stitch sewing machine having a vertically operable needle bar for operating a needle secured thereto, and a presser bar substantially parallel to said needle bar disposed spaced from the needle bar in a direction corresponding to a direction of advancement of a workpiece to be stitched onto a garment, a presser de-

vice secured to a lower end of said presser bar, a guide mechanism for guiding a folded strip workpiece to be stitched as trimming on a garment comprising, in combination, a needle plate having a first portion provided with a slot for the needle to move therethrough during a stitching operation, said needle plate having a narrower projecting second portion having a part thereof extending longitudinally from said first portion and having parallel longitudinal edges substantially normal to the transverse axis of the first portion, said projecting portion constituting a portion of the needle plate farthest removed from the presser bar, said first portion having a longitudinal edge parallel to the longitudinal edges of the second portion of the needle plate, an angle member secured extending transversely to said needle plate projecting laterally from a longitudinal edge of said projecting portion of said needle plate parallel to said first portion, and having an upper flat surface substantially flush with the upper surface of said needle plate, a second plate disposed substantially normal to the needle plate and having an end edge aligned with the longitudinal edge of said first portion of the needle plate which is disposed nearest to it and arranged at a level lower than the needle plate, said second plate having opposite end portions, one of said opposite end portions being disposed remote from said needle plate offset from the opposite end portion thereof and disposed at a higher level than the last-mentioned opposite end portion and at a level lower than the needle plate, a rocker arm of stepped profile pivotally secured to said offset portion and extending toward said needle plate, pivot means pivotally mounting said rocker arm on said offset portion providing a pivot point about which the arm pivots, said rocker arm having a length substantially equalling the distance between the pivot point and said longitudinal edge of said first portion of the needle plate nearest said second plate, a slide slidably along said arm, a vertical bearing plate on said slide having a side facing the needle and presser bars, said side extending vertically to a level above the level of said needle plate, a support removably secured to a lower end of said presser bar, a presser foot rotatably mounted on said support for bearing on said portion of said needle plate provided with said slot, said presser foot having a slot corresponding to the first mentioned slot for the needle to move therethrough in carrying out a stitching operation, an auxiliary presser foot pivotally supported by said presser foot about an axis substantially parallel to an axis about which said presser foot rotates with respect to said support and displaceable in a vertical direction, said auxiliary presser foot being disposed to bear on the portion of said needle plate to which said angle member is secured and having a vertical surface cooperating with said vertical bearing plate to effectively guide said workpiece longitudinally through said guide mechanisms, a lateral extension on said auxiliary presser foot disposed spaced above and in correspondence with said angle member secured to the needle plate and substantially equal in length to said angle member.

2. A two thread stitch sewing machine according to claim 1, in which an eccentric washer is rotatably secured to said second plate supporting the said arm rocker abutting an edge of said arm and positionable in selected angular positions for providing a fine adjustment of the angular position of the arm.
